Ware, Mass.

Application August 8, 1955, Serial No. 526,948

4 Claims. (Cl. 280—11.13)

Our invention relates to new and useful improvements in a ski construction of the land or water type and is directed more particularly to the provision of a pre-stressed ski and to an improvement in the means for producing same.

It is the principal object of our invention to provide a novel and improved construction of the type in which certain components of the ski are stressed or tensioned prior to assembly of the ski and there is the further provision of additional other innovations in skis which will eliminate certain now present objectionable inconvenience and which will operate with a maximum amount of ease and with a minimum degree of effort.

One of the primary purposes of our invention is to provide structural and operational improvements in devices of the class to which reference has been made, which improvements not only simplify the structure as such, but also provide important distinct advantages in strength, durability, efficiency and the like.

As is well known, the ski throughout most of its length is slightly arched, so that without any weight applied thereto, a small section of the ski touches the plane at the rear and a small section touches the plane at the front. When the weight of a skier is placed on the ski, the ski is depressed so that it touches continuously from front or upturn to rear or heel, thus providing a dependable even support or uniform full bearing throughout the snow contacting length of the ski.

The stiffness of the spring preferably should gradually increase as the middle of the arch, or footrest portion, gradually approaches the plane, so that the said middle portion does not pass below the horizontal plane. Any such sagging of the local section supporting the weight (i. e. the foot rest section) creates a brake action and lessens the weight supporting bearing. This condition emphasizes the importance of the ski retaining the form initially imparted thereto.

In the utilizing of skis, it is highly desirable that the central part of the ski be arched. Likewise it is desirable that this arch formation be maintained when the skis are not in use. The invention herein described offers means whereby the ski may be initially provided with the desired degree of arching prior to the complete fabrication of same, all to the end that the retention of the arched formation throughout the life of the ski is insured.

It is another object of our invention to provide a construction whereby the rigidity of the ski or the resistance thereof to longitudinal bowing may be predetermined, it being readily understood and appreciated that varying degrees of flexure are required for users of different weights.

It is still another object of the invention to provide a ski construction which is substantially uniformly flexible over its entire length.

Other prime objects of our invention include; first, the securing of a higher degree of accuracy and greater degree of variety in the manner of work performed therewith than has heretofore been possible with prior devices

2

known in the art; second, the attainment of a higher speed of construction and assembly of the device due to its simplification of design and its unique composition of parts; third, the provision of an improved ski construction, which may be made more economically and with fewer operations in the manufacture of its parts, as well as in the assembly of the same, than prior devices known in the art; fourth, the provision of a construction which may be readily installed with respect to the various purposes for which it is intended, and fifth, the provision of such other improvements in and relating to ski constructions of the type above referred to as are hereinafter described and claimed.

With the above primary objects in view, it is another object of our invention to provide a construction of the above described character in which the number of operating parts is greatly reduced and which is compact in accordance with the demands and desires of manufacturers and purchasers alike and which is not only distinctive in its appearance and practical in its value but also reliable in its operation and efficient in its use.

It is a still further object to provide a device which is constructed of relatively simple parts which are adapted to be readily assembled and which when once assembled are positively and securely retained in operative relationship and which cannot be readily separated from each other.

Further objects and advantages of our invention will become apparent as the following description proceeds, and the features of novelty which characterize the same will be pointed out with particularity in the claims annexed to and forming part of this specification.

In the accompanying drawing, we have illustrated a complete example of a physical embodiment of the invention in which the parts are combined and arranged in accordance with one mode which we have devised for the practical application of the principles of the invention. It will however be understood that changes and alterations are contemplated and may be made in these exemplifying drawings and mechanical structures, within the scope of the claims, without departing from the principles of the invention.

The above cited objects, we accomplish by means of such structure and relative arrangement of parts thereof as will fully appear by a perusal of the description below and by various specific features which will be hereinafter set forth.

To these ends, various other and ancillary features and advantages and objects of our invention will become more readily apparent as the description proceeds. Our invention consists in certain features of novelty, in a mode of operation, and in the combination, organization, and arrangement of parts as will be hereinafter more particularly pointed out in the claims hereunto annexed and more fully described and referred to in conjunction with the accompanying drawings wherein:

Fig. 1 is a top plan view of a ski construction of the invention;

Fig. 2 is a side elevational view of the structure shown in Fig. 1;

Fig. 3 is an enlarged sectional elevational view on the line 3—3 of Fig. 1;

Fig. 4 is an enlarged sectional elevational view on the line 4—4 of Fig. 1;

Fig. 5 is an enlarged sectional elevational view on the line 5—5 of Fig. 1;

Fig. 6 is an enlarged sectional elevational view on the line 6—6 of Fig. 1; and

Figs. 7 and 8 are enlarged sectional elevational views showing modified forms of certain details of the construction of our invention.

In the above mentioned drawing annexed hereto and forming a part of this specification, we have presented

but one general embodiment of the invention which is deemed preferable, but it is for purposes of illustration only. The invention is susceptible of incorporation in other modified forms coming equally within the scope of the claims hereof. Changes may be made in various respects and within the scope of the appended claims without departing from broad aspects and spirit of the invention.

In the following description and claims, various details are identified by specific names for convenience. These names however are intended to be as generic in their application as the art will permit.

Referring now to the drawing more in detail, in which similar characters of reference indicate corresponding parts in the several figures and referring more particularly to the preferred form of my invention selected for illustrative purposes, we have shown a ski reinforcement construction which comprises a forward metal toe plate member 2 and a rearward metal heel plate member 4. Same are held together in spaced relation by means of a pair of parallel spaced elongated runner or rail members 6 and 6 preferably of metal which are fixed to the members 2 and 4 at their respective opposite ends, as shown, so as to form the general outline of a ski construction.

A plurality of metallic pin or dowel members 8 are 25 provided and connect the opposed runner members 6 and 6 at spaced points along the lengths thereof, as shown. They may be press fitted, threaded, or otherwise engaged as by screws or the like. Said members 8 function to strengthen the reinforcement construction and to hold the members 6 and 6 in the desired spaced relation.

A tensioning member which may be in the form of a high tensile strength steel wire 10 or the like is provided and extends from the member 4 (where it is held in a manner shortly to be described) forwardly through suitable aligned openings 12 in the pin members 8 to a vertically disposed opening 14 in the member 2 and is then returned through other aligned openings 12 in the pin members 8 back to the member 4.

Each free end of the member 10 is introduced to the member 4 through a vertically disposed conical or tapered opening 22 rearwardly of the forward face of the member 4, as best shown in Fig. 5.

A tapered plug member 24 is receivable in the opening 22 in such a manner that the tensioning member 10 may be led into the opening 22 and held adjacent the member 24, when the desired tension of the member 10 has been attained. The plug 24 is provided with a knurled surface and the plug may be forced upwardly into the opening 22 securely so as to grip the extremity of the member 10 and to hold same. As the member 24 is moved upwardly, the member 10 is wedged in the opening so as to securely clamp the member 10 and prevent undesired movement thereof.

At the forward or toe plate 2, the member 10 is merely passed through the vertical opening 14 from the top to the bottom (or vice versa, as may be desired).

In any event, the construction is such that, by the pulling of the ends of the member 10 at the rearward end of the device, the reinforcing structure may be caused to bow so as to produce the arched configuration aforementioned.

Such pulling amounts to pre-stressing and the same is accomplished until the desired degree of arching is attained whereat the plugs 24 are set into position so as to hold the ends of the member 10 secure relative to the heel plate whereby the arched configuration is retained.

Such pre-stressing having been attained, the remainder of the assembly of the ski may be accomplished.

Laminations of wood or the like comprising a top lamination 30 and a bottom lamination 32 extend in the lateral direction of the ski so as to sandwich the forward plate member 2 and the rearward plate member 4 and so as to be disposed between the runner or rail members 6 and 6, all as shown in Fig. 6.

Said laminations are disposed on opposite sides of (above and below) the pin members 8 so that air spaces 34 between the laminations are provided between each pair of pin members and the members 2 and 4. In this manner, the weight of the construction is lessened and the resiliency thereof is obviously enhanced.

Rivet members 38 may be provided, if desired, which extend vertically through the pin members 8 and through the laminations 30 and 32, as best shown in Fig. 3, so as to retain the components in their relative positions.

On the upper surface of the lamination 30 and on the lower surface of the lamination 32, layers of plastic 40 and 42 respectively may be disposed between the opposed members 6 and 6 and over the length of the ski from the forward tip of the toe plate to the rearward tip of the heel plate.

Same may be secured to the laminations 30 and 32 by any conventional bonding material.

If desired, the rail members 6 and 6 may be provided with steel edges 50 on the lower sides thereof, which edges may be held in place by means of rivets 52 or the like extending through the adjacent member 6.

As modified forms of the construction, reference will now be made to Figs. 7 and 8.

In Fig. 7, each extremity of the member 10' is shown as being introduced to the member 4' through aligned openings 20' extending inwardly from the forward face of the member 4' and communicating with a conical or tapered vertically disposed opening 22' rearwardly of the forward face.

A tapered plug member 24' is receivable in the opening 22' in such a manner that the tensioning member 10' may be led into the opening 22' and held adjacent the member 24', when the desired tension of the member 10 has been attained. The plug 24' has a knurled surface and may be forced upwardly into the opening so as to grip the extremity of the member 10' to hold same.

As the member 24' is moved upwardly, the member 10' is wedged in the opening so as to securely clamp the member 10' and prevent undesired movement thereof.

A vertically disposed opening 26' of a somewhat reduced diameter may be provided and may extend downwardly from the top of the member 4' so as to communicate with the opening 22'. When it is desired to remove the plug 24', same may be driven downwardly and outwardly by means of a tool which may be inserted through the opening 26'.

As another modified form of the feature of the invention, we have shown, in Fig. 8, an opening 22" in the plate member 4" which is conical in its configuration and tapers inwardly from the top face of the member 4".

In this instance, a tapered plug 24" may be inserted downwardly so as to wedge a tensioning member 10" extending inwardly into the opening 22" from the forward face of the member 4" as shown.

In any event, the construction is such that by the pulling of the ends of the member 10' or 10" at the rearward end of the device, the reinforcing structure may be caused to bow so as to produce the arched configuration aforementioned.

When the desired degree of arching is attained, the plugs 24' or 24" are set into position so as to hold the ends of the members 10' or 10" respectively secure relative to the structure whereby the arched configuration is retained. Such pre-stressing having been attained, the remainder of the assembly of the ski may be accomplished.

In the modification shown in Fig. 7, top and bottom laminations 30' and 32' are disposed between rails 6 (as in Fig. 6) and abut member 4'. In the modification shown in Fig. 8, similar laminations 30" and 32" are disposed between rails 6 (as in Fig. 6) and abut member 4".

While we have illustrated and described the invention as embodied in a specific arrangement, we do not intend to be limited to the details shown since various modifications and structural changes may be made without de-

parting in any way from the spirit of the invention. Without further analysis, the foregoing is intended to so fully reveal the gist of our invention that others can, by applying current knowledge, readily adapt it to various applications without omitting features which, from the standpoint of prior art, fairly constitute essential characteristics of the generic aspects of this invention, and therefore, such adaptations should and are intended to be comprehended within the meaning and range of equivalence of the claims below.

What it is desired to claim and secure by Letters Patent of the United States is:

1. Ski construction comprising in combination, metallic toe and heel plates, elongated metallic runners having opposite ends secured to said toe and heel plates and having inner sides spaced apart transversely between said toe and heel plates, a plurality of dowels relatively spaced along said runners intermediate upper and lower sides thereof and having opposite ends connected to inner sides of said runners, elongated laminations disposed between inner longitudinal sides of said runners and extending over said plates and above and below said dowels providing elongated air spaces between inner adjacent faces thereof and the inner ends of said plates, said dowels provided with openings therethrough for tension wires, and elongated wires extending along the air spaces and through the openings in said dowels and being connected to said toe and heel plates so as to be under tension to bow the ski slightly upwardly from the lower side thereof between said toe and heel plates.

2. Ski construction comprising in combination, toe and heel plates, elongated spaced runners having opposite ends secured to adjacent inner ends of said toe and heel plates, a plurality of dowels relatively spaced along and between said runners intermediate upper and lower sides thereof, elongated strips of laminations disposed between inner longitudinal sides of the runners and extending over said toe and heel plates and above and below said dowels providing elongated air spaces between inner adjacent faces thereof and the inner ends of said toe and heel plates, said dowels being provided with openings there-

through, and an elongated wire extending along the air spaces and through the openings in said dowels and being connected to said toe and heel plates for tensioning to bow the ski slightly upwardly from the lower side thereof between said toe and heel plates.

5 3. A prestressed ski construction comprising, spaced metallic toe and heel plates, spaced elongated metallic runners having opposite ends secured to said toe and heel plates, a plurality of dowels relatively spaced between 10 said runners and having opposite ends connected to said runners, said dowels being provided with openings therethrough, an elongated tensioning wire extending through the openings in said dowels and connected to said toe and heel plates for the bowing of said runners between said 15 toe and heel plates, and elongated laminations disposed between inner longitudinal sides of said runners and above and below said dowels and extending over and under said toe and heel plates.

4. A prestressed ski construction comprising in combination, spaced toe and heel plates, spaced elongated runners having opposite ends secured to adjacent inner ends of said toe and heel plates, a plurality of apertured dowels relatively spaced between said runners intermediate upper and lower sides thereof, an elongated tension 25 wire extending through the apertures in said dowels and being connected to said toe and heel plates for the flexing of said runners between said toe and heel plates, and elongated strips of lamination disposed between inner sides of said runners in their stressed condition and extending over said toe and heel plates and above and below said dowels.
